UNITED STATES PATENT OFFICE.

JOHN LLEWELLYN DAVIES, OF Highbury, England.

ELECTRIC-ARC LAMP.

SPECIFICATION forming part of Letters Patent No. 701,016, dated May 27, 1902.

Application filed January 15, 1901. Serial No. 43,376. (No model.)

To all whom it may concern:

Be it known that I, JOHN LLEWELLYN DAVIES, a subject of the Queen of Great Britain and Ireland, residing at 11 Horsell road, Ronalds Road, Highbury, London, England, have invented certain new and useful Improvements in or Connected with Arc-Lamps, (for which I have made application for patent in Great Britain on the 1st of November, 1900, No. 19,595;) and I do hereby declare the following to be a full, clear, and exact description of the invention, such as will enable others skilled in the art to which it appertains to make and use the same.

This invention for improvements in or connected with arc-lamps relates to an improved framework for the lamp, to an improved means for attaching the regulating-coils to the framework of the lamp, to an improved means for counterbalancing the cores of the regulating-coils, and to improved means for holding the inclosing globe and reflector, and to an improved means for connecting the brake-mechanism dash-pot and regulating mechanism.

In the accompanying sheets of illustrative drawings, Figure 1 is an elevation of an enclosed arc-lamp constructed according to this invention, and Fig. 2 is an inverted sectional plan showing the regulating-solenoids and their connecting mechanism, and Fig. 3 is a sectional plan of the lower part of the lamp. Fig. 4 is a detail view of the vibration-spring of the lamp.

The framework of the lamp comprises the top or crown plate *a*, the coil-plate *b*, hung from the crown-plate *a* by side rods *b'*, a main or central tube *c*, held in the coil-plate *b*, the cover-plate *d* of the regulating-mechanism chamber fixed on the lower end of the central tube *c*, and the globe or cylinder-cap *e*, hung from the cover-plate *d* by side rods *e'*.

The regulating-coils *l m'* are inserted between the coil-plate *b* and the crown *a* and are forced against insulating flanged nipples *a'*, fixed on the crown-plate *a* by nuts *b'*, screwing on the lower ends of the side rods *b'* and bearing against the coil-plate *b*, the side rods being insulated from the coil-plate.

On top of the main tube *c* is a cap *c'*, having a bracket or arm *c'*, supporting the axis

g' of a double pulley *g*, having fixed in its larger diameter a flexible cord *h'*, connected to the upper-carbon holder *h*, and on its smaller diameter a flexible cord *h''*, connected to a weight *h'''*, sliding on a guide-rod *h''*, fixed between the bracket or arm *c'* and the cover-plate *d*.

The cores *l m* of the regulating-coils *l m'* are connected to opposite ends of the lever *n*, fulcrumed on a screw-stud *c'*, fixed in a bracket-ring *c'*, fixed on the central tube *c*, the cores being connected in alternate-current lamps to the lever by coil or spiral springs *l''* for taking up the vibration. The dash-pot cylinder *o* is pivoted to the lever *n* and has a ball-valve *o'* at its top. The piston *o''* of the dash-pot is connected by its rod *o'''* to the cover-plate *d*.

The regulating mechanism consists of a disk *p*, guided on rods *p'*, fixed in the globe-plate *e* and having a central hole, through which the carbon passes. One edge of the disk is connected to the lever *n* by the link *n'*, and there is a small counterweight *n''* on the opposite edge, that normally rests on a stop on the globe-plate *e*.

The lower-carbon side rods *r* are suspended and insulated from horizontal screws *r'*, screwing into the globe-plate *e*, and are connected at the bottom by a bridge *r''*, supporting a hollow tail-screw *s*, in which is a sliding plunger *s'*, forced upward by a helical spring *s''*, bearing on a set-screw *s'''* in the bottom of the tail-screw. The plunger *s'* bears against the under side of the lower-carbon holder *t*, that also serves to support the globe *e'*.

An ornamental ring *v'* is fitted to the bottom of the case *v*, fixed at its upper end to the crown-plate *a*, and the reflector *v''* is fixed to the ring by buttons *v'''*, screwing into the ring.

The current passes to the positive terminal +, fixed in the coil-plate *b*, through the series coil *l*, to a terminal *f* on the cover-plate *d'*, thence by a flexible connection *d''* to the globe side rods *r*, lower-carbon holder *t*, carbons, upper-carbon holder *h*, flexible cord *h'* to the negative terminal - on the coil-plate.

The shunt-coil *m'* is connected directly across the positive + and negative - terminals.

What I claim, and desire to secure by Letters Patent, is—

1. The improved means of supporting the regulating-solenoids consisting of a crown-plate, insulating-nipples fixed on the crown-plate, a coil-plate, side rods insulated from the coil-plate, and forcing the coil-plate toward the crown-plate, coils inserted between the plate and over the nipples on the crown-plate substantially as described.

2. The combination with a grip device controlling the feed or descent of the upper carbon, of means for counterbalancing the upper-carbon holder, consisting of a double pulley, two flexible cords fixed to the double pulley, the upper-carbon holder and the guided counterweight fixed to the cords substantially as described.

3. The means of suspending the lower-carbon holder and globe consisting of a fixed horizontal plate, insulated side rods pivoted by horizontal pivots to the horizontal plate, a bridge connecting the lower ends of the side rods, a tail-screw screwing in the bridge, a spring-plunger in the bridge, and the carbon-holder and globe-support resting on the plunger substantially as described.

4. The controlling mechanism consisting of the solenoids, solenoid-cores, lever, frame-tube, ring fixed on the frame-tube, screw-stud fixed in the ring and serving as the fulcrum of the lever, and the coil or spiral springs situated in holes in the lever and connecting the lever to the solenoid-cores substantially as described.

5. The dash - pot arrangement for arc-lamps, consisting of the controlling-lever, the dash-pot cylinder, links connecting the cylinder to the controlling-lever, the lamp-frame, the dash-pot piston pivoted to the frame, and a ball-valve on the top of the dash-pot cylinder substantially as described.

6. The lamp-casing consisting of the crown-plate, a cylindrical casing fixed at its top to the crown-plate, an L-ring fixed to the bottom of the casing, a reflector and removable screw-bottom for fixing the reflector to the ring substantially as described.

In testimony whereof I have affixed my signature in presence of two witnesses.

JOHN LLEWELLYN DAVIES.

Witnesses:

ALBERT JONES,
HERBERT C. BOLWELL.
